(57) **CLAIM**

The ornamental design for a magnifying glass, as shown and described.

DESCRIPTION

FIG. 1 is a top, left, front perspective view of the magnifying glass according to my design;

FIG. 2 is a top plan view thereof;

FIG. 3 is a bottom view thereof;

FIG. 4 is a rear elevational view thereof;

FIG. 5 is a front elevational view thereof;

FIG. 6 is right side elevational view thereof; and,

FIG. 7 is a left side elevational view thereof.

The broken lines form no part of the claimed design.

1 Claim, 7 Drawing Sheets

FIG. 2

FIG. 4

FIG. 5

FIG. 6

FIG. 7
